UNITED STATES PATENT OFFICE.

JOHN V. CUNNIFF, OF NEW BEDFORD, MASSACHUSETTS, ASSIGNOR TO DRAPER COMPANY, OF HOPEDALE, MASSACHUSETTS, A CORPORATION OF MAINE.

LET-OFF MECHANISM FOR LOOMS.

SPECIFICATION forming part of Letters Patent No. 747,302, dated December 15, 1903.

Application filed June 13, 1903. Serial No. 161,273. (No model.)

To all whom it may concern:

Be it known that I, JOHN V. CUNNIFF, a citizen of the United States, and a resident of New Bedford, county of Bristol, State of Massachusetts, have invented an Improvement in Let-Off Mechanism for Looms, of which the following description, in connection with the accompanying drawings, is a specification, like characters on the drawings representing like parts.

In positively-driven let-off mechanism for looms, such as the well-known Bartlett let-off or the Roper let-off, shown in United States Patent No. 647,815, it is necessary for the weaver to unclamp the friction-collar and turn the worm-shaft by the hand-wheel in the Bartlett type or by the ratchet in the Roper construction whenever it is desired to turn the warp-beam backward or forward. This is necessary for various reasons—as, for instance, after making a pick-out.

In either form of apparatus above referred to the operation specified is slow, and in practice the weaver's hands are very apt to become soiled, as so many oily parts of the mechanism have to be handled.

This invention has for its object the production of simple means whereby when desired the warp-beam can be readily and instantaneously released from its actuating mechanism, the release being effected by one hand and leaving the beam free to be turned any distance. The releasing is effected so quickly and the parts to be handled are so few in number that there is little liability of soiling the hands of the weaver, it being manifest that it is very important a weaver should keep his hands clean, as otherwise he is apt to injure the cloth.

The novel features of the invention will be described fully in the subjoined specification and particularly pointed out in the following claims.

Figure 1 is a side elevation of a portion of a let-off mechanism of a loom with one form of the invention embodied therein. Fig. 2 is a partial vertical section thereof on the line 2 2, Fig. 1, looking toward the left. Fig. 3 is a detail on the line 3 3, Fig. 2, looking

down, showing the transmitting means partly broken out between the warp-beam and its actuating member; and Fig. 4 is an enlarged view, partly in longitudinal section, of the clutch or coupling interposed between the beam and the actuating member therefor.

Referring to Figs. 1 and 2, the warp-beam W, having an attached gear B, the upright actuating or driving shaft d, the worm d^x , fast thereon, the ratchet d' , pawl d^2 , and pawl-carrier d^3 , the link d^4 , connecting the pawl-carrier with a moving part of the loom, as the lay, and the friction device F for the shaft d may be of substantially well-known construction and form no part of this invention, the pawl and ratchet rotating said shaft step by step. A bracket E, attached to the loom side A, has an elongated bearing e for a transmitting-shaft E^x rotatably mounted therein, and a worm-gear e^x and a pinion g are shown mounted on the shaft E^x in continuous mesh with the worm d^x and beam-gear B, respectively. The shaft E^x projects some distance beyond each end of the bearing e, and herein the pinion g on the inner end of the shaft is shown secured thereto by its hub g' , while the worm-gear e^x is loose on the shaft. The outer end of the hub e' of the worm-gear e^x is herein shown as having teeth or projections e^2 on its outer end, forming one member of a clutch or coupling, the inner end of the hub being adjacent the outer end of the bearing e, Figs. 2 and 3. Upon the outer end of the shaft E^x , projecting beyond the hub e' , is mounted the other member f of the clutch or coupling, shown as recessed in Fig. 4 and having at its inner end teeth or projections f^2 to engage the teeth or projections e^2 . The member f is splined at f^x , Fig. 4, to the shaft E^x and normally held in operative position by a spring s^x , the outer end of the latter abutting against a collar f^3 , secured to the shaft by a set-screw 3. An annular lip or enlargement f^4 is made on the outer end of the member f to facilitate its movement manually, and by reference to Fig. 4 it will be seen that the spring-receiving recess in the coupling member f is of greater diameter than the collar f^3 .

Ordinarily the spring will maintain the clutch members in coöperative position, and thereby the worm-gear e^x will rotate with the transmitting-gear E^x , and the warp-beam will be rotated from the actuating shaft or member d . When, however, the weaver finds it necessary to turn the warp-beam backward or forward, all that is necessary is for him to grasp the clutch member f , which by its 10 shape forms a convenient knob, and draw it outward on the shaft E^x , thereby releasing the clutch, and the warp-beam can then be turned backward or forward as much as desired. The releasing of the clutch is effected 15 easily and instantly with one hand, and it will be manifest that it is unnecessary for the weaver to take hold of any of the oily parts of the loom in order to disconnect the warp-beam and its actuating mechanism.

20 With the structure herein shown it will be seen that the friction device F is not disturbed in any way by the release of the beam, so that when the latter has been manipulated, as desired, by hand the parts are in condition 25 for immediate resumption of work, the release of the clutch or coupling member f by the weaver being followed by the automatic clutching of the parts due to the action of the spring s^x .

30 The invention is not restricted to the precise construction and arrangement herein shown, as various changes or modifications may be made therein without departing from the spirit and scope of the invention.

35 Having fully described my invention, what I claim as new, and desire to secure by Letters Patent, is—

40 1. In let-off mechanism for looms, a warp-beam, a positively-driven actuating member, a transmitting-shaft having a fast and a loose gear thereon, one of said gears coöperating with the warp-beam and the other with the actuating member, and a clutch to normally effect rotation of the loose gear with the 45 shaft, release of the clutch permitting the warp-beam to be turned independently of the actuating member.

50 2. In let-off mechanism for looms, a warp-beam, an actuating member therefor, driven by a moving part of the loom, gears on the beam and driving member, a transmitting-shaft having mounted upon it gears in mesh with the beam and driving-gears, one of the

gears on the shaft being fast thereon, and means to uncouple manually the other shaft- 55 gear from the shaft.

3. In let-off mechanism for looms, a warp-beam, an actuating member therefor, driven by a moving part of the loom, gears on the beam and driving member, a transmitting-shaft having a gear fast thereon in mesh with the beam-gear, a second gear loose on the shaft and in continuous mesh with the driving-gear, and a clutch to connect the loose gear with or disconnect it from the transmitting-shaft. 60

4. In let-off mechanism for looms, a warp-beam having an attached gear, an actuating-worm driven by a moving part of the loom, a transmitting-shaft having a pinion fast thereon in mesh with the beam-gear, a fixed bearing in which the shaft is rotatably mounted, a worm-gear loose on said shaft and in continuous mesh with the worm, a clutch member on said worm-gear, a coöperating clutch 70 member rotatable with the shaft and movable longitudinally thereon into and out of engagement with its fellow, and a spring to effect coöperation of the clutch members and thereby connect the worm-gear with the 80 shaft.

5. In let-off mechanism for looms, a warp-beam having an attached gear, an actuating-worm driven by a moving part of the loom, a transmitting-shaft having a pinion fast thereon in mesh with the beam-gear, a fixed bearing in which the shaft is rotatably mounted, a worm-gear loose on said shaft and in continuous mesh with the worm, said pinion and worm-gear being located at opposite ends of the shaft-bearing, a clutch one member whereof rotates with the worm-gear and the other member with the shaft, the latter member being mounted on the outer end of the shaft and manually movable longitudinally thereof in one direction to render the clutch inoperative, and a spring to effect coöperation of the clutch members. 85 90

In testimony whereof I have signed my name to this specification in the presence of two subscribing witnesses. 100

JOHN V. CUNIFF.
